UNITED STATES PATENT OFFICE.

JOSEPH W. JONES, OF CORNING, NEW YORK, ASSIGNOR TO INGERSOLL-RAND COMPANY, OF JERSEY CITY, NEW JERSEY, A CORPORATION OF NEW JERSEY.

OIL GOVERNOR FOR COMPRESSOR ENGINES.

Application filed May 27, 1922. Serial No. 564,101.

To all whom it may concern:

Be it known that I, JOSEPH W. JONES, a citizen of the United States, and a resident of Corning, county of Steuben, State of

5 New York, have invented a certain Oil Governor for Compressor Engines, of which the following is a specification accompanied by drawings.

This invention relates to engine driven 10 compressors, but more particularly to a discharge line pressure and speed controlled regulator for the engine, of the type disclosed in Letters Patent of the United States No. 1,278,160 granted to W. F. Treiber and myself on September 10th, 1918 15 for governing mechanism for compressor engines.

In such a governor a chamber may be provided with a fluid actuated plunger which 20 is connected to an inlet valve of the engine, a pump responsive to the engine speed supplies fluid, as for instance oil, to the plunger chamber, a by-pass pilot valve controls the supply of fluid to the chamber, 25 means responsive to receiver or discharge line pressure are connected to move the pilot valve in a direction to increase the supply of fluid to the plunger chamber and thereby decrease the speed of the engine, and oppos- 30 ing stabilizing means actuated by the plunger are connected to move the pilot valve in the opposite direction tending to decrease the supply of fluid to the plunger chamber and check the movement of the plunger un- 35 til the engine speed again increases. In the above mentioned patent a system of reducing levers, shown as a pantograph, is connected between the plunger and the pilot valve.

40 The object of the present invention is to simplify the construction above briefly outlined and produce a governor operating on substantially the same principles, but cheaper to manufacture and having certain me- 45 chanical and operative advantages and features of construction which will hereinafter appear.

To all of these ends the invention consists of the combinations of elements and ar- 50 rangement of parts having the general mode of operation substantially as hereinafter fully described and claimed in this speci- 55 fication and shown in the accompanying drawings, in which—

Figure 1 is a top plan view partly in

horizontal section of so much of a steam driven compressor having my governor applied thereto, as will serve to illustrate the invention;

Figure 2 is a side elevation of the gover- 60 nor partly in vertical section through the pilot valve on the line 2—2 of Figure 1 looking in the direction of the arrows;

Figure 3 is a side elevation of the gover- 65 nor partly in vertical section through the plunger casing and pilot valve casing on the line 3—3 of Figure 1 looking in the direction of the arrows;

Figure 4 is an end elevation of the gover- 70 nor partly in vertical section through the pilot valve and regulating mechanism on the line 4—4 of Figure 1 or the line 4—4 of Figure 3 looking in the direction of the arrows, and

Figure 5 is a detail horizontal sectional 75 top plan view through the governor on the line 5—5 of Figure 4, with the exception that the maximum speed screw is indicated conventionally for clearness, although the line of section is actually taken at a point 80 below said maximum speed screw.

Referring to the drawings, Figure 1 indicates diagrammatically, the high pressure side of a duplex steam driven compressor having my improved governor applied 85 thereto. To the engine bed or frame A are connected the compressor cylinder B, and the steam cylinder C having the piston D. The steam cylinder C is provided with a valve chest E having the inlet F and the 90 exhaust outlet G. A piston valve H operates in the chest E and is carried by a valve rod J connected to the rod K adapted to be actuated by a suitable eccentric (not shown) on the main shaft L of the 95 machine.

Variably movable auxiliary cut-off valves O and P are mounted within the piston valve H upon the valve stem Q which is connected to the rod R adapted to be actuated by another suitable eccentric (not shown) on the main shaft L. The auxiliary cut-off valves O and P as shown are carried on reversely threaded portions of the valve stem Q and said valve stem is longitudinally 100 movable but also rotatable so that rotation of the stem in one direction or the other moves the auxiliary cut-off valves towards 105 and from each other to vary the cut-off. This portion of the machine is substantially 110

like that disclosed in the aforesaid Patent No. 1,278,160.

A governor of the type to which this invention relates automatically proportions the speed of the compressor to the demand for air by varying the position of the engine cut-off valves. The governor is preferably located on the high pressure side of the compressor and includes an oil pump S, preferably of the gear type and conveniently driven from the crank shaft L as by means of the chain T and sprockets U and V, for delivering oil under pressure to a chamber W, preferably in the form of a cylinder, and containing a weighted plunger X, operatively connected to control the cut-off valves, as by means of the rack Y on the plunger and the pinion Z on the shaft a having the sprocket b connected by the chain c to the sprocket d on the valve stem Q which controls the auxiliary cut-off valves O and P. As the governor plunger X is forced upwardly in the chamber W by increase of oil pressure, the sprocket b will be rotated in a direction to separate the auxiliary cut-off valves O and P and thus decrease the supply of steam to the steam engine.

The admission of oil to the plunger chamber W is controlled by a by-pass pilot valve e, the position of which in its valve chest f is determined by the relative position of the governor plunger X.

Stabilizing effects are obtained by means of suitable reducing levers connecting the pilot valve e with the plunger X, and also with an air actuated weighted lever g pivoted at h on the bracket j. When the compressor speed is such as to create sufficient oil pressure to force the plunger outwardly in its chamber W, the pilot valve e will open and prevent further lifting of the plunger X until another increase of speed occurs.

I have found that a suitable and sensitive air controlled device for actuating the weighted lever g may consist of a sylphon comprising a cup k and associated parts suitably supported on the cover plate o of the casing p containing the by-pass pilot valve e and the pump S. A sylphon in the usual form of an expansible and contractable corrugated cylinder q is supported within the cup k, and a pointed pin r carried in a socket s bears underneath the weighted lever g. The sylphon is subject to receiver pressure or in this instance is subject to discharge line pressure and is connected to the discharge line t as by means of the pipe u which leads to the bottom of the sylphon. Increase of discharge line pressure will cause the sylphon to expand and move the weighted lever g upwardly.

The valve stem v of the by-pass pilot valve e is pivotally connected at the point

w to a stabilizing lever x which in turn is fulcrumed on a pin y carried by the weighted lever g. A link z pivotally connects the outer end of the stabilizing lever x to one arm 2 of the bell crank lever 3 pivoted at 4 to the bracket 5 and having its other arm 6 extending opposite a transversely slidable pin 7 movable in the wall of the chamber W and extending into a tapered groove 8 in the side of the plunger X. From the construction so far described, it will be obvious that the upward movement of the pilot valve e due to the upward movement of the weighted lever g will be opposed and compensated for by the upward movement of the plunger X, because as the transversely movable pin 7 is forced outwardly by the tapered groove or cam surface 8 on the plunger X, the bell crank lever 3 will be rocked in a direction to move the stabilizing valve lever x downwardly. The object of this construction is to bring the speed of the compressor back to an intermediate point. The weighted lever g may be provided with an adjusting spring 9 for close adjustment and a minimum speed screw 10 acting as a stop for the shorter end of the lever g which limits the movement of said lever and prevents the valve e from being entirely closed.

In the operation of the pump S, oil is pumped from the pump chamber having the rotary gears 12, only one of which is shown, and the oil is conducted through the pipe 13 to the compartment 14 in the valve casing f. From thence the oil passes in through the apertures 15 in the valve cage 16, and with the valve in the position shown in Figures 2 and 4, the oil may pass out through the apertures 17 and 18 in the valve cage 16 to the oil discharge chamber 19 and thence through the aperture 20 controlled by the maximum speed screw or valve 21 to the space 22 in the casing and back to the oil pump through the oil inlet aperture 23 in the pump casing. In this way there is a continual by-pass and flow of oil from the pump through the valve chamber and back to the pump, and this flow is controlled by the pilot valve e due to the cooperation between the valve heads on the valve and the valve seats provided on the valve cage 16 all as disclosed in the aforementioned Patent No. 1,278,160.

The inlet compartment 14 in the valve casing as shown in Figure 3 is directly connected by means of the passage 24 with the interior of the plunger chamber W, and the pressure supplied to the plunger chamber will be dependent upon the amount of opening of the by-pass through the pilot valve e back to the suction side of the oil pump S and also upon the adjustment of the maximum speed screw 21. In order to increase the maximum speed of the machine the

screw 21 is screwed outwardly and for a slower maximum speed the screw is turned inwardly in order to throttle the opening 20.

The operation of the device is like that described for the device disclosed in the above mentioned patent, but I am not to be understood as limiting my invention to the precise form and details of construction shown in the accompanying drawings and 10 described in this specification, except as defined in the appended claims, because those skilled in the art to which this invention relates may devise equivalent devices without departing from the spirit of my invention.

15 I claim:

1. In an engine driven compressor, a discharge line pressure and speed controlled regulator, comprising a chamber, a fluid actuated plunger therein connected to an inlet valve of the engine, a pump responsive to the engine speed for supplying fluid to said chamber, a by-pass pilot valve for controlling the supply of fluid to said chamber, means responsive to discharge line pressure 20 for moving said pilot valve in a direction to increase the supply of fluid to the plunger chamber, and opposing means actuated by the plunger, and including a cam and follower, operatively connected to move said 25 pilot valve in the opposite direction tending to decrease the supply of fluid to the plunger chamber.

2. In an engine driven compressor, a discharge line pressure and speed controlled 30 regulator, comprising a chamber, a fluid actuated plunger therein connected to an inlet

valve of the engine, a pump responsive to the engine speed for supplying fluid to said chamber, a by-pass pilot valve for controlling the supply of fluid to said chamber, 40 means responsive to discharge line pressure for moving said pilot valve in a direction to increase the supply of fluid to the plunger chamber, and opposing means actuated by the plunger, and including a cam on the 45 plunger and a follower cooperating therewith, operatively connected to move said pilot valve in the opposite direction tending to decrease the supply of fluid to the plunger chamber. 50

3. In an engine driven compressor, a discharge line pressure and speed controlled regulator, comprising a chamber, a fluid actuated plunger therein connected to an inlet valve of the engine, a pump responsive 55 to the engine speed for supplying fluid to said chamber, a by-pass pilot valve for controlling the supply of fluid to said chamber, means responsive to discharge line pressure for moving said pilot valve in a direction to increase the supply of fluid to the plunger chamber, and opposing means actuated by the plunger and including a longitudinally tapered groove on the plunger 60 forming a cam surface and a movable pin 65 cooperating with said groove and operatively connected to move said pilot valve in the opposite direction tending to decrease the supply of fluid to the plunger chamber.

In testimony whereof I have signed this 70 specification.

JOSEPH W. JONES.
